UNITED STATES PATENT OFFICE.

LUCIAN M. ZELL, OF BOSTON, MASSACHUSETTS, ASSIGNOR TO THE AMERICAN GEM COMPANY, OF MAINE.

DESIGN FOR A PIN.

SPECIFICATION forming part of Design No. 32,463, dated April 10, 1900.

Application filed February 5, 1900. Serial No. 4,143. Term of patent 3½ years.

To all whom it may concern:

Be it known that I, LUCIAN M. ZELL, a citizen of the United States, residing at Boston, in the county of Suffolk and State of Massachusetts, have invented and produced a new and original Design for a Pin, of which the following is a specification, reference being had to the accompanying drawings, forming part hereof, in which—

Figure 1 is a plan view of a pin, showing my design. Fig. 2 is a side view looking in the direction of the arrow, and Fig. 3 is a top view.

My design, as shown in the drawings, is

for a double-tined pin with the tines somewhat bowed or curved for part of their length and running in the same general direction from the head. (See Fig. 1.) At A the pin is bent over at a right angle with the plane through the tined parts, as shown in Figs. 2 and 3.

I claim—

The design for a pin as herein shown and described.

LUCIAN M. ZELL.
